(57) **CLAIM**

What is claimed is the ornamental design for a lamp, as shown and described.

DESCRIPTION

FIG. 1 is a top perspective view of an embodiment of the lamp that includes the word "FAN."

FIG. 2 is a left side view of the lamp of FIG. 1.

FIG. 3 is a front elevation view of the lamp of FIG. 1.

FIG. 4 is a right side view of the lamp of FIG. 1.

FIG. 5 is a rear elevation view of the lamp of FIG. 1.

FIG. 6 is a top plan view of the lamp of FIG. 1.

FIG. 7 is a bottom plan view of the lamp of FIG. 1.

FIG. 8 is a bottom perspective view the lamp of FIG. 1.

FIG. 9 is a top perspective view of an embodiment of the lamp that includes the word "MOM."

FIG. 10 is a left side view of the lamp of FIG. 9.

FIG. 11 is a front elevation view of the lamp of FIG. 9.

FIG. 12 is a right side view of the lamp of FIG. 9.

FIG. 13 is a rear elevation view of the lamp of FIG. 9.

FIG. 14 is a top plan view of the lamp of FIG. 9.

FIG. 15 is a bottom plan view of the lamp of FIG. 9.

FIG. 16 is a bottom perspective view the lamp of FIG. 9.

FIG. 17 is a top perspective view of an embodiment of the lamp that includes the word "DAD."

FIG. 18 is a left side view of the lamp of FIG. 17.

FIG. 19 is a front elevation view of the lamp of FIG. 17.

FIG. 20 is a right side view of the lamp of FIG. 17.

FIG. 21 is a rear elevation view of the lamp of FIG. 17.

FIG. 22 is a top plan view of the lamp of FIG. 17.

FIG. 23 is a bottom plan view of the lamp of FIG. 17; and,

FIG. 24 is a bottom perspective view the lamp of FIG. 17. The broken line disclosure represents portions of the lamp which form no part of the claimed design.
